UNITED STATES PATENT OFFICE.

JULIUS HAVAS, OF SARBOGARD, AUSTRIA-HUNGARY.

PLOWING MECHANISM.

1,127,759.

Specification of Letters Patent.

Patented Feb. 9, 1915.

Application filed March 28, 1914. Serial No. 828,004.

To all whom it may concern:

Be it known that I, JULIUS HAVAS, a subject of the King of Hungary, residing at Sarbogard, Austria-Hungary, have invented 5 certain new and useful Improvements in Plowing Mechanism, of which the following is a specification.

This invention relates to an apparatus for mechanical plowing, which on the one hand makes it possible to use any self-propelled engine for plowing, and on the other hand insures favorable distribution of forces and a better utilization of the parts subjected to heavy loads.

10 15 A construction according to this invention is illustrated, by way of example, in the accompanying drawing in which—

Figure 1 shows in plan the cable drum for moving the pulley truck, Fig. 2 shows the 20 cable drum truck attached behind the engine, Fig. 3^a shows on a larger scale a cross-section on the line 3^a—3^a of Fig. 3. Fig. 3 shows the pulley truck, while Fig. 4 shows 25 diagrammatically the apparatus in operation.

The apparatus according to this invention comprises the following parts: 1. Any self-propelled engine arranged in such a manner that its winding drum can be reversed. 2. A 30 cable drum truck attached to the engine (Fig. 1). 3. A pulley truck (Fig. 3). 4. A guide pulley. 5. A balance-plow. 6. A wire cable driving the plow, and 7. A wire cable pulling the pulley truck.

35 The cable drum *c* pulling the pulley truck, can be arranged either under or in front of the engine (Fig. 1) but the drum *a* must be capable of being driven from the main shaft of the engine. The drum *a* is mounted 40 loosely on a shaft *b* and drives the cable drum *c* only when, on the chain controlled from the driver's seat being released, the bell crank lever *e* allows the jaws *g*¹ *g*² of a clutch, controlled by a spring *f*, to come into engagement. The cable drum then winds the 45 cable *h* pulling the pulley truck and passing over a guide roller *i* which, for the purpose of insuring uniform winding, is connected to a device which will now be described.

50 On the spindle of the cable drum is mounted a toothed bevel wheel *n*¹ engaging with a toothed bevel wheel *n*². The latter drives by means of a spindle *o* the worm *h* which, during one revolution of the spindle of the 55 cable drum also makes one revolution and turns a toothed wheel *l* to the extent of one

tooth. The toothed wheel *l* has twice as many teeth as the number of windings which can be arranged side by side in the longitudinal direction on the drum. When the spindle of the cable drum has made half as many revolutions as the number of teeth of the toothed wheel *l*, the toothed wheel *l* makes half a revolution, and the rod *m* carrying the roller *i*, is moved in the direction of the axis of the cable drum to the extent of the length of the cable drum. At the second half revolution of the toothed wheel *l*, the roller is again moved toward the other end of the cable drum. In that way, a uniform winding of the cable is insured.

60 The cable drum truck (Fig. 2) is attached, in working, by means of two iron bars *N* directly behind the engine, so that it cannot alter its position relatively to the engine. The cable drums are driven from the engine by means of belts, chains or the like. The pulley *a*' drives the spindle *d* only when, on a chain connected to a bell crank lever *L* being released, a spring *F* brings into engagement with each other the jaws *b*¹ *b*² of a clutch or coupling. At other times the pulley *a*' revolves idly. On the spindle *d* is secured a toothed bevel wheel *e*' driving by means of a toothed bevel wheel *f*' the main 75 shaft *h*' on which are loosely mounted the cable drums *A*¹, *A*². Each of the cable drums is secured to one jaw *i*² of a coupling and driven by the engine when the jaws *i*' of the coupling are brought into engagement 80 with the jaws *i*² by means of the levers *B*¹ *B*². The said levers are connected together by a rod *C* which can be reciprocated from the driver's seat by any desired means. The device for throwing the drums in or 85 out of gear is arranged in such a manner that the jaws of only one coupling can be in engagement with each other at a time, so that only one cable drum is driven at a time. The said cable drum winds the cable, while 90 the other drum rotates idly, and is moved by the unwound, inoperative, cable.

95 Uniform winding of the wire cable on the drum is insured by the following arrangement: On the main shaft is mounted 105 a bevel wheel *K* driving a bevel wheel *M* mounted on the same spindle with a toothed wheel *M*¹. The latter wheel drives by means of toothed wheels *M*², *M*³, a toothed wheel *m*² which drives a worm *r* provided on the 110 same spindle. This worm at each revolution rotates the toothed wheel *s* to the ex-

tent of one tooth and the said toothed wheel moves the driving rod u by means of the rod t . On the rod u are mounted rollers $x^1 x^2$ which guide the cable g driving the plow.

5 The engine is mounted on four wheels.

The pulley truck (Fig. 3) comprises a frame consisting of longitudinal members $y^1 y^2 y^3$ and transverse members $f^2 f^3$. Between the superposed longitudinal members $y^2 y^3$ is left an opening large enough for the reception of a pulley T secured to a spindle d' . Over the said pulley passes the indirectly working cable g which is raised into the plane of the pulley T by guide rollers $E^1 E^2$ mounted on the longitudinal member y' , whereby any slipping of the cable out of the guide pulley is prevented.

For the purpose of increasing the stability of the pulley truck, the outer road wheels O^1, O^2 are made about 40 cm. wide, and hollow, so that they can be filled, before starting work, with water or some other easily removable material, in order to increase their weight. In order to prevent the vehicle from slipping in the direction of the cable traction, the inner road wheels O^3, O^4 are provided with detachable annular steel flanges $I^1 I^2$, the said flanges being secured to the wheels by hooks K^1 . When not working, in transport, the water can be discharged from the outer wheels, while the flanges $I^1 I^2$, after turning the hooks K^1 rotatably mounted on the same, can be removed or raised so that they do not touch the ground.

The advance of the pulley truck during working is effected by means of the cable h passing over a guide roller H . The only alteration of the plow which is required consists merely in arranging next to the road wheel running on the ground which has not been yet plowed, a guide pulley H^1 (Fig. 4) used for guiding the indirectly working cable.

45 The working with the new apparatus can be seen in Fig. 4. The plow is working for instance on a plane representing an irregular rectangle. At one edge stands the pulley truck, at the other edge the self-propelled engine to which is connected the drum truck and to the front end of which is secured the drum device for pulling forward the pulley truck by means of the cable h . According to Fig. 4, the cable drum A^2 is working and drawing the plow toward itself by means of the cable g passing around the pulley T of the pulley truck, while the wire cable is being unwound from the loose cable drum A^1 .

What I claim as my invention and desire 60 to secure by Letters Patent is:—

1. Plowing mechanism comprising in combination a plow, a self-propelled engine, three winding drums adapted to be driven thereby, a pulley-truck carrying a guide-pulley, a cable secured to the plow at one

end and wound on one winding drum, a second cable secured at one end to the plow, passing around the guide-pulley and wound on a second winding drum, and a third cable secured to the pulley-truck, passing over a fixed guide, and wound on the third winding drum.

2. Plowing mechanism comprising in combination a plow, a self-propelled engine, three winding drums adapted to be driven thereby, a pulley-truck carrying a guide-pulley, a cable secured to the plow at one end and wound on one winding drum, a second cable secured at one end to the plow, passing around the guide-pulley and wound on a second winding drum, a third cable secured to the pulley-truck, passing over a fixed guide, and wound on the third winding drum, and means operable from the driver's seat for throwing the third winding drum into and out of gear.

3. Plowing mechanism comprising in combination a plow, a self-propelled engine, a truck carrying two winding drums and rigidly connected to the engine, means controllable from the driver's seat for coupling and uncoupling the winding drums severally with the engine shaft, a third winding drum driven independently of the said two winding drums, a pulley-truck carrying a guide-pulley, a cable secured to the plow at one end and wound on one winding drum, a second cable secured at one end to the plow, passing around the guide-pulley and wound on a second winding drum, and a third cable secured to the pulley-truck, passing over a fixed guide, and wound on the third winding drum.

4. Plowing mechanism comprising in combination a plow, a self-propelled engine, three winding drums adapted to be driven thereby, a pulley-truck carrying a guide-pulley, a cable secured to the plow at one end and wound on one winding drum, a second cable secured at one end to the plow, passing around the guide-pulley and wound on a second winding drum, a third cable secured to the pulley-truck, passing over a fixed guide, and wound on the third winding drum, and means whereby the first winding drum is coupled to the engine shaft when the second winding drum is uncoupled, and vice versa.

5. Plowing mechanism comprising in combination a plow, a self-propelled engine, three winding drums adapted to be driven thereby, a pulley-truck carrying a guide-pulley, a cable secured to the plow at one end and wound on one winding drum, a second cable secured at one end to the plow, passing around the guide-pulley and wound on a second winding drum, a third cable secured to the pulley-truck, passing over a fixed guide, and wound on the third winding drum, and means, comprising two

movable clutch members connected together, adapted to clutch and unclutch the first and second winding drums alternately.

6. Plowing mechanism comprising in combination a plow, a self-propelled engine, three winding drums adapted to be driven thereby, a pulley-truck carrying a guide-pulley, a cable secured to the plow at one end and wound on one winding drum, a second cable secured at one end to the plow, passing around the guide-pulley and wound on a second winding drum, a third cable secured to the pulley-truck, passing over a fixed guide, and wound on the third winding drum, and means for guiding the cables uniformly along the width of the drums in both directions.

7. Plowing mechanism comprising in combination a plow, a self-propelled engine, three winding drums adapted to be driven thereby, a pulley-truck carrying a guide-pulley, a cable secured to the plow at one end wound on one winding drum, a second cable secured at one end to the plow, passing around the guide-pulley and wound on a second winding drum, a third cable secured to the pulley-truck, passing over a fixed guide, and wound on the third winding drum, and cable-guiding means comprising guide-rollers mounted on rods adapted to be reciprocated across the width of the drums by means of worm and crank gear operated by the drums.

8. Plowing mechanism comprising in combination a plow, a self-propelled engine, a truck rigidly connected to the engine and having hollow wheels adapted to be filled

with water, two winding drums on said truck adapted to be driven by the engine, a third winding drum driven independently of the said two winding drums, a pulley-truck carrying a guide-pulley and having hollow wheels adapted to be filled with water, a cable secured to the plow at one end and wound on one winding drum, a second cable secured at one end to the plow, passing around the guide-pulley and wound on a second winding drum, and a third cable secured to the pulley-truck, passing over a fixed guide, and wound on the third winding drum.

9. Plowing mechanism comprising in combination a plow, a self-propelled engine, three winding drums adapted to be driven thereby, a pulley-truck carrying a guide-pulley, annular flanges, pins having hooked ends rotatably mounted on said flanges and adapted to fix said flanges to the road wheels of said pulley-truck, a cable secured to the plow at one end and wound on one winding drum, a second cable secured at one end to the plow, passing around the guide-pulley and wound on a second winding drum, and a third cable secured to the pulley-truck, passing over a fixed guide, and wound on the third winding drum.

In testimony whereof I have signed my name to this specification in the presence of two subscribing witnesses.

JULIUS HAVAS.
